UNITED STATES PATENT OFFICE.

WILLIAM M. CARR, OF WHEELING, WEST VIRGINIA.

APPARATUS FOR MAKING COKE AND GAS.

1,070,666.

Specification of Letters Patent. Patented Aug. 19, 1913.

Application filed December 11, 1911. Serial No. 664,950.

To all whom it may concern:

Be it known that I, WILLIAM M. CARR, a citizen of the United States, residing at Wheeling, in the county of Ohio and State 5 of West Virginia, have invented certain new and useful Improvements in Apparatus for making Coke and Gas, of which the following is a specification.

This invention relates to apparatus for 10 making coke and gas; and it comprises stationary regeneratively operated firing means having oppositely located firing ports spaced away from each other, means for successively introducing a plurality of transportable firing chambers between and in engagement with said firing ports, each such firing 15 chamber being adapted for ready engagement and disengagement with such ports and being provided with a contained closable coking and gas-forming chamber or 20 retort, and a stationary gas-removing conduit adapted to be made to engage with such retorts successively as the corresponding inclosing fire chamber comes into register with 25 such firing ports; all as more fully herein-after set forth and as claimed.

For a number of reasons the continuous manufacture of satisfactory coke is somewhat difficult in practice. Where it is attempted to pass coal as a continuous prism or stream through a heating chamber, the resulting coke is inevitably more or less crushed and disintegrated. The cooling of the incandescent coke coming from such a 30 chamber is furthermore a difficult and unpleasant operation. It is usually done by quenching with water which causes the generation of clouds of steam and usually results in a wet coke which requires re-drying. The discontinuous coke-making operations give better coke but are relatively slow, since the operator must wait for the heating up and cooling of the furnace chambers, retorts, or ovens. As concerns the gas making operation in the discontinuous processes, 35 the gas is necessarily of different qualities at different stages in the operation, and the larger the mass of coal so treated the greater, of course, is the volume of gas of 40 special quality given off at any special stage in the operation.

In the present invention I have devised a new type of apparatus for the manufacture of gas and coke combining the advantages 45 of the continuous and discontinuous operations. In this apparatus, the operation is

continuous as regards the firing means but is discontinuous as regards the particular portion of coal at any time under treatment, successive relatively small portions of coal 60 being treated by continuously operating firing and gas removing means. The coal is not handled or moved during its conversion into coke and therefore suffers a minimum of disintegration; and it is cooled in the apparatus in which it is made, thereby avoiding the necessity for quenching. As many relatively small portions of coal as may be desired may be under treatment at once in different stages of the operation, thereby 65 70 equalizing the quality of the gas which is given off.

In the present invention I provide a plurality of transportable coking chambers, each being provided with an individual firing chamber. These firing chambers are provided with ports or openings adapted for engagement with firing ports of a regeneratively operating heating apparatus. These firing ports may communicate with the usual checkerworks and are so spaced apart that firing chambers may be brought between them and into engagement with such ports. Advantageously, there is a line of rails between the spaced firing ports on which may 80 travel trucks carrying one or more firing chambers. Each such firing chamber has within it a closable or closed retort. Located above the regenerative firing means is a stationary gas removing means and 85 means for connecting it successively to each of the coking chambers temporarily under treatment. Where the firing chambers are carried, as is usually the case, on trucks, a coking chamber may be loaded with coal and 90 a truck pushed forward until the ports of the firing chamber make engagement with the corresponding spaced ports of the regeneratively heated apparatus, and the gas removing means brought into engagement 95 with the retort. Firing is now proceeded with until the contents of the retort are coked to the degree desired when the firing chamber and contained retort are pushed forward by moving the truck, the gas removing means being disengaged and the top 100 closed with any suitable closure. The contents of the retort may now be allowed to cool spontaneously. As the retort and chamber containing the finished coke are removed from the regenerative firing device 105 another firing chamber with a retort carry-

ing a fresh charge of coal may be substituted. As will be perceived, so far as the gas removing means and the firing means are concerned, the operation is continuous, but as regards the coking retorts or the coking operation, it is discontinuous.

Of course more than one regenerative apparatus may be provided; and where such is the case, a plurality of regenerative firing devices may be simultaneously treating a plurality of coking retorts in different stages of the operation, the gas from each such coking retort being delivered to a suitable main. This averages out the temporary fluctuations in the quality of the gas. But of course with a single regenerative firing device, the gas coming from all the retorts may be delivered into a common collecting chamber or gasometer and the fluctuations in the quality of the gas thereby averaged out.

In the accompanying illustration I have shown, more or less diagrammatically, certain embodiments of the described invention. In this showing, Figure 1 is a side elevation of a complete installation showing two of the combined firing chambers and retorts, one such chamber being in operative position and the other awaiting engagement; Fig. 2 is a vertical elevation seen from one end of the apparatus; and Fig. 3 is a vertical section on an enlarged scale of one of the combined firing chambers and retorts described.

In the showing of Fig. 1, element 1 is a regenerator of a common type connecting with stack 2. Air ports 3 may lead up from this regenerative structure into engagement with the firing chamber. As shown the regenerator may only deliver hot air, the necessary combustible, such as oil or gas, being introduced through ports 4. Mounted on a truck 5 running on wheels 6 and track 7 are shown two of the combined firing chambers and retorts, respectively 7^a and 7^b, the latter being shown in engagement with regenerative firing means while the former is awaiting engagement. Both are provided with opposite open flame ports 8 adapted to engage the firing ports of the regenerative device. Each is shown as mounted on standards 9 having means for tilting, 10. This is convenient in emptying the retorts. The top of the retort in operation delivers its gas through connection 11 valved at 12 to main 13.

Referring now to Fig. 2, the elements just described are designated by the same reference characters. In addition there is shown elevating means 14 engaging the cover or top and adjustable connection 15 for the gas removing means. On platform 16 is shown car 17 adapted for supplying fresh coal to the retorts. Cars 18 may be used for removing the cooled coke.

In Fig. 3 is shown the combined firing chamber and retort on a larger scale. As there shown, 19 is a fire chamber of any suitable refractory material in a steel shell 20. The open ports (8) previously referred to, provide for transverse passage of flame through the chamber. Within the firing chamber is a retort or container 21 of iron, clay or any other suitable material supported on blocks 22 and having an open top 75 registering with the open top of the firing chamber. As shown, the latter open top is provided with a coned opening 23 within which rests a cap 24 of any suitable material provided with lifting lugs 25. This cap is centrally provided with a coned opening 26 having an offset 27 within which a gasket 28 of asbestos rope or the like may be located. Resting within this coned opening is a disengageable water sealed apparatus 29, 80 having a coned lower end adapted to enter the opening and remove the gases, and having at its upper end a depending wall 30 adapted to enter within a trough formed by an upward prolongation 31 of the gas connection (11) previously referred to. This device may be used as a water seal. As will be seen, the cap may be readily lifted into and out of engagement with the gas connection.

The operation of this structure is believed to be obvious from the foregoing. The regenerative devices (1) being in operation, flames sweep across the firing chamber (7^b) temporarily in operation, alternately passing in each direction in a well understood way. The coal coking in the retort chamber 21 gives off its gas which passes through 11 and 13 to a place of use (not shown), being scrubbed and purified in the usual way. When the evolution of gas ceases and the coking operation is carried as far as may be desired, element 29 is lifted by 14 out of the way and a temporary closure is placed in the opening in the cap of the firing chamber. The firing chamber may now be run off and the contents of the retort allowed to cool naturally. The next retort in order (7^a) having been filled with coal from 17, is run into place in engagement with the ports of the regenerative heating device, water seal 29 is lowered into place and the operation is repeated. Gas from 13 may be supplied through 4 to the firing ports.

What I claim is:

1. In apparatus for making gas and coke, a stationary regenerative device having spaced and opposite firing ports, a transportable fire chamber having opposite open flame ports adapted to register with said firing ports, a coking retort within said fire chamber and having a gas outlet, stationary gas removing means located near said stationary regenerative device and adapted for 130

connection with said outlet, and means for bringing a plurality of such transportable fire chamber's successively between such firing ports and into and out of engagement therewith.

2. In apparatus for making coke and gas, a stationary regenerative heating device having a pair of vertical extensions with open firing ports and spaced apart, a platform between such extensions, a stationary gas removing connection located in proximity to such extensions, a truck-mounted fire chamber upon such platform having open flame-ports and adapted for being wheeled into and out of disengagement with such firing ports, a coking retort within such fire chamber and means for connecting the retort with such gas removing connection.

3. In apparatus for making gas and coke, a transportable truck-mounted fire chamber having open flame-ports adapted for engagement and disengagement with stationary firing means, a coking retort mounted within said chamber and having a gas outlet and means for making a temporary connection between such outlet and a gas main.

4. In apparatus for making gas and coke, a transportable truck-mounted fire chamber having open flame-ports adapted for engagement and disengagement with stationary firing means, a coking retort mounted within said chamber and having an open mouth, a removable top closing the fire chamber and the open mouth of the retort, such top having a gas outlet and means for making a temporary connection between such outlet and a gas removing device.

5. In apparatus for making gas and coke, a transportable truck-mounted fire chamber having walls of refractory material and provided with open flame ports adapted for

registry with regenerator firing ports, a depending open-mouthed retort within said fire chamber, a removable top for said fire chamber registering with and closing the mouth of said retort and a water-sealed removable gas connection engaging an orifice in said top.

6. In apparatus for making gas and coke, a transportable truck-mounted fire chamber having walls of refractory material, provided with lateral opposite open flame ports adapted to register with regenerator firing ports and an upwardly flaring mouth, a depending open-mouthed retort within said fire chamber, a coned centrally orificed top fitting within said flaring mouth and closing the retort mouth, and a gas removing device removably mounted in the central orifice of such top.

7. In apparatus for making gas and coke, a gas main having an inlet with a water seal inlet, a transportable truck-mounted fire chamber having walls of refractory material, provided with lateral opposite open flame ports adapted to register with regenerator firing ports and an upwardly flaring mouth, a depending open-mouthed retort within said fire-chamber, a coned centrally orificed top fitting within said flaring mouth and closing the retort mouth, and a gas removing connection removably mounted in the central orifice of such top, said connection having a depending wall adapted to enter the water seal.

In testimony whereof, I affix my signature in the presence of two subscribing witnesses.
